UNITED STATES PATENT OFFICE.

TELESPHORE C. DEMERS, OF LEBANON, NEW HAMPSHIRE.

WARP-TENSION EQUALIZER.

Application filed December 1, 1926. Serial No. 151,972.

This invention relates to the let-off mechanism of looms, and one object is to provide means whereby the brake shoe may be quickly adjusted to the diameter of the beam head 5 without removing the shoe from the head, and another object of the invention is to provide means whereby the brake band may be quickly released from the beam head and re-applied thereto without necessitating a 10 re-adjustment to obtain the desired tension. The invention also has for its object the provision of a shock absorber which may be quickly and easily removed from the shoe and in which play or back lash will be eliminated, the invention seeking further to simplify the construction of the shock absorber 15 without any loss of efficiency. Other objects will appear incidentally in the course of the following description, and the invention resides in certain novel features which will be particularly pointed out in the appended 20 claims.

In the accompanying drawings:

Figure 1 is an end elevation of a portion 25 of a loom adjacent the warp beam showing one embodiment of the present invention;

Fig. 2 is a plan view, with parts in section, of the device;

Fig. 3 is an enlarged front elevation with 30 parts in section;

Fig. 4 is a longitudinal section;

Fig. 5 is a detail section on the line 5—5 of Fig. 4;

Fig. 6 is an enlarged detail plan view of 35 a portion of the brake shoe, and

Fig. 7 is an enlarged detail end elevation of the cam for releasing the brake band from the beam head.

In the drawings, the reference numeral 1 40 indicates a portion of a loom frame to which is rigidly secured a bracket 2 which extends upwardly and inwardly therefrom and is provided at its upper end with a shelf 3, the purpose of which will hereinafter appear.

The beam head 4 is of any approved construction and is secured upon the trunnion 5 of the warp beam in the usual or any convenient manner. Resting upon the beam head is a brake shoe 6 which is provided at 50 one end with a laterally projecting lug 7 having a notch 8 in its outer end. To the opposite end of the shoe 6 is secured one end of a brake band 9 which is preferably of resilient metal and is carried under the beam head so as to bear against the same 55 and terminates in eyes 10 receiving a stud

or pin 11, upon which is pivotally mounted a tension bolt or screw 12 in a well-known manner. The tension bolt or screw 12 extends through the notch 8 at the end of the shoe and is equipped at its upper extremity with a wing nut 13 acting upon a tension spring 14 coiled around the bolt or screw between the nut and the lug 7 whereby the band 9 may be drawn into yieldable frictional contact with the beam head in the usual manner. Carried by the lug 7 and extending outwardly therefrom is a base plate 15 which supports the lower end of the spring 14, as clearly shown in the drawings, and on the said base plate at an intermediate point in the length thereof and beyond the end of the lug 7 is a post 16. Pivotally mounted upon the upper end of the said post is a release finger 17, the inner end of which is forked, as shown at 18, and spans the screw or bolt 12 to engage and bear upon the spring 14. The outer end of the said finger 17 is turned downwardly, as shown at 19, and an eccentric or cam 20 is pivotally 80 mounted upon the said down-turned end 19 with its periphery arranged to bear upon the end of the base plate 15, as shown. This cam or eccentric 20 is carried by a smooth stud 21 having its head 22 countersunk in the outer side of the eccentric, and in the periphery of the eccentric are grooves 23 extending longitudinally thereof and adapted to engage a stop 24 mounted in the end of the base plate 15 whereby the eccentric will 90 be held in a set position. It is to be observed that the grooves 23 have their walls beveled or inclined so that the grooves are V-shaped and the end of the stop 24 is tapered or conical so that, while the engagement of the end of the stud in any one of the grooves will hold the eccentric against accidental release, the application of slight force to the eccentric will overcome the restraining influence of the stop and permit 95 the eccentric to rotate about the stud 21. Spaced circumferentially about the eccentric are openings 25 which are internally threaded to receive a lever or handle 26 which is shown as a small rod of circular 100 cross section having a threaded end whereby it may be engaged in any one of the sockets or openings 25 as may be most convenient when the parts have been initially set.

When it is desired, for any reason, to release the brake band from the beam head, as, for instance, when the warp is to be 110

pulled back, after picking out, and arranged for starting over, the operator swings the lever or handle member 26 downwardly so that the high part of the eccentric will be brought into opposition to the base plate 15 whereby the compression finger 17 will be rocked upon the post 16 and the forked end 18 thereof will compress the portion of the spring 14 between the same and the base plate, thereby releasing the band 9 from the beam head. When the warp has been rearranged, a quick tap upon the handle member 26 will restore the eccentric 20 to its initial position and permit the spring 14 to exert the same tension as before upon the band. The operation is repeated at the opposite end of the warp beam and a start without a light or a heavy place in the cloth is assured. It will be understood, of course, that a beam head and the parts cooperating therewith is supplied at each end of the warp beam, and the unreleased brake band will hold the warp until the released band has been again placed in engagement with the beam head.

The shoe 6 is equipped on its under side with the usual metal lining plate 27 which extends from the lug 7 to the opposite end of the shoe and has one end extended partly under the said lug and permanently secured thereto by a countersunk screw 28, as shown clearly in Fig. 4. Near the lug 7, the shoe is constructed with a short longitudinally extending slot 28' receiving the body of a stud 29 which is upset against or riveted to the plate 27, also as shown in Fig. 4. Bearing against the outer side of the shoe is a washer 30 which is held in place by a headed screw 31 inserted through the washer 40 to engage the stud 29, and the said washer, as shown in Fig. 6, has the same contour as the slot 28 but is slightly wider so that it will overlap the walls of the slot and constitute an abutment for the screw head. When the parts are assembled in the working position, the washer preferably extends across the slot, as shown in Fig. 6, and the screw is turned home against the washer so that the plate 27 will be held firmly to the inner concave surface of the shoe. Should the beam head become worn or for any other reason there should be an improper fit between the plate 27 and the beam head, a shim plate 32 is fitted between the shoe and the plate very easily and quickly. To accomplish this result, the screw 31 is loosened and the plate 27 is thus permitted to slightly separate from the shoe, remaining attached thereto, however, by the screw 28. The shim plate is constructed in one edge with a notch 33 of sufficient width to pass around the stud 29 and it will, therefore, be seen that, after the lining plate 27 has been released in the manner described, 65 the shim plate may be inserted edgewise

between the lining plate and the inner surface of the shoe with the notch alined with the stud and may be pushed laterally into position, after which the lining plate may be pressed back against the shim plate and all the parts returned to the position shown in Fig. 6. The shim plate can thus be easily fitted in place without requiring the removal of the tension device from the beam head and one or more shim plates may be inserted as may be necessary.

The shoe is so arranged with respect to the beam head that the tension bolt 12 and the parts associated therewith will be presented at the rear side of the loom while the end of the shoe to which the brake band 9 is attached will be presented forwardly. Intermediate the ends of the shoe, a pair of lugs or bosses 34 rise therefrom, and these bosses are preferably integral with the shoe, as shown. Disposed between the bosses is a plunger 35 which is retained in place by a pivot pin 36 inserted through the lugs or bosses and the plunger, as shown. The plunger is normally tangential to the shoe and the beam head but will have sufficient pivotal movement to accommodate itself to the varying angular relations between the plunger and the loom frame as the tension device moves with the beam head. The plunger is longitudinally split or slotted, as shown at 37, in its rear portion, the front end of the slot coinciding with the pivot holes to receive the pin 36 and the walls of the slot are adjusted toward each other by a clamping screw 38 inserted diametrically through the plunger across the slot whereby, when the screw is turned home, the plunger will be compressed and held in the proper frictional engagement with the pivot pin. I also provide set screws 39 mounted in the front sides of the respective lugs or bosses 34 and turned home against the pivot so that movement between the pivot and the bosses will be checked. It will be understood that the set screws 39 and the clamping screw 38 will be adjusted so as to eliminate all lost motion between the pivot and the bosses and the plunger respectively but will not bind upon the engaged parts to such an extent as to lock them against all relative movement. Firmly secured upon the shelf 3 is a box-like casting into which the front end of the plunger 35 projects. This casting has an opening 40 in its back wall 41 to admit the plunger and the said opening extends through the outer edge of said wall, as shown clearly in Fig. 3. The corresponding side of the casting is entirely open, as shown at 42 in Fig. 2, while the front wall 43 of the casting serves as an abutment to limit the movement of the plunger in the operation of the mechanism. A side wall 44 extends between the inner edge of the front wall 43 and the back

wall 41 so as to impart the necessary strength and rigidity to the device and a top wall 45 also extends between the front wall 43 and the back wall 41 for the same purpose, it being noted that the casting entirely encloses the front end of the plunger and the parts associated therewith, except at the outer side of the casting and the said parts are, consequently, protected 5 against damage from possible accidental contact with other parts of the loom while at the same time they are accessible from the outside of the loom and may be easily removed when necessary. The back wall 41 of 10 the box-like casting projects above the top wall 45 of the same, and to the rear side of the said wall is secured a guiding and retaining plate 46, the lower end of which is arcuate, as shown at 47, whereby it may fit 15 around the reduced end 48 of a collar 49 which is secured upon the plunger adjacent the front end of the same and extends through the recess or notch 40 in the said wall 41. Cooperating with the retaining and 20 guiding plate 46 is a lower guide plate 50 secured to the wall 41 of the box-like casting and projecting above the lower side of the recess or notch 40 to engage the collar 49, as shown clearly in Figs. 4 and 5. The retaining and guide plate 46 is constructed 25 with a vertical slot 51 through which the fastening bolts are inserted into the wall 41 so that the said plate may be adjusted to properly engage the collar 49 and compensate for wear upon the contacting surfaces. Upon the extremity of the plunger are mounted pick-adjusting nuts 52 which are in threaded engagement with the end of 30 the plunger and are set so that, when the parts are at rest, the distance between the abutment front wall 43 of the box-like casting and the nuts will be equal to the extent of movement of the warp in one pick. Fitted 35 upon the plunger loosely and bearing against the rear faces of the plates 46 and 50 is a washer 53 and bearing against the rear side of the said washer and encircling the plunger is a short sleeve 54 which may, if preferred, be formed integral with the said 40 washer 53. The plunger has a short threaded portion which is normally disposed at the rear end of the sleeve 54, and upon this threaded portion are mounted adjusting nuts 45 55 which are set to impart the desired tension to a spring 56 which is housed within the said sleeve 54 and is shown as a compression spring coiled around the plunger but may be a spring band or a soft wooden block or any other preferred form of buffer or cushion or shock absorber according to the requirements of any given conditions. The nuts 55, as well as the nuts 52, are provided with sockets 57 in all their faces so 50 that they may be easily engaged by a pin 55 or a wrench when they are to be turned and

the desired adjustment thereby attained. The pick-adjusting nuts may be adjusted accurately so as to obtain a very fine adjustment of the let-off mechanism, it being possible to set the said nuts a quarter of an inch 70 or more from the abutment and also to bring them against the abutment or within a few thousandths of an inch from it.

In the operation of the loom, there is a well-known tendency to impart a jerky or intermittent movement to the warp beam. The tension device moves with the warp beam so as to retain the desired tension upon the warp but if this intermittent jerky movement of the warp beam is not overcome the weaving is uneven so that thick or thin places occur in the cloth. When the beam moves under this intermittent impulse, the plunger 35 will move forwardly until the pick-adjusting nuts or the end of the plunger impinges against the abutment 43 provided by the front wall of the box-like casting, the movement being yieldably checked by the spring 56 so that the jerk upon the warp beam is absorbed and the warp is, consequently, permitted to pass to the harness and other mechanism of the loom in an even steady manner. As soon as the strain upon the warp beam is released, the spring 56 will expand and, consequently, return the plunger and the shoe 6 with the cooperating devices to the initial position, thereby overcoming all tendency of the warp to feed irregularly and eliminating 80 the thick or thin places in the cloth. If it should be necessary, for any reason, to remove the plunger and the parts mounted thereon from the brake shoe 6, the retaining plate 46 is raised so that it will be entirely clear of the reduced end of the collar 49. The pivot pin 36 is then withdrawn, whereupon the plunger with the nuts, the collar 49, the spring 56 and its housing may be removed laterally through the open side of 85 the box-like casting, the plunger being, of course, tilted so that it will clear the lugs or bosses 34. The assembly can be just as easily and quickly returned to the operative position by moving the plunger inwardly through the open side of the box-like casting, this facility of removal and replacement being advantageous when it is desired to change the warp beam or replace or adjust just the cushion device.

Having thus described the invention, I claim:

1. In an apparatus for the purpose set forth, the combination of a brake shoe, a brake band attached at one end to the shoe and equipped at its opposite end with a tension bolt and a tension spring cooperating with the end of the shoe to yieldably retain the band under a desired tension, a rocking finger carried by the shoe and engaged at one end with the said spring, and

means for rocking said finger whereby to compress the spring and permit release of the friction band.

2. In an apparatus for the purpose set forth, the combination of a brake shoe, a brake band attached at one end to one end of the shoe, a bearing member at the opposite end of the shoe, a tension bolt attached to the free end of the band and passing through the last-mentioned end of the shoe and the said bearing member, a spring co-acting with the said bolt to maintain the tension upon the brake band, a finger mounted for rocking movement upon the said bearing member and engaged at one end with the spring, and an eccentric pivotally mounted upon the outer end of the finger and engaged with the said bearing member whereby to rock the finger and compress the spring to permit release of the brake band.

3. In an apparatus for the purpose set forth, the combination of a brake shoe, a brake band attached at one end to one end of the shoe, a tension device carried by the free end of the band and cooperating with the opposite end of the shoe, said tension device including a spring, a base plate projecting from the last-mentioned end of the shoe, a rocking finger mounted between its ends upon said base plate and having its forward end engaged with the said spring, an eccentric pivotally mounted upon the rear end of the finger and bearing upon the base plate, means for rocking the said eccentric, and means for yieldably retaining the eccentric in a set position.

4. In an apparatus for the purpose set forth, the combination of a brake shoe, a brake band attached at one end to one end of the shoe, a tension device carried by the opposite end of the brake band and cooperating with the corresponding end of the shoe, said tension device including a compression spring, a base plate projecting from the said end of the shoe, a post on said base plate beyond the end of the shoe, a rocking finger mounted upon the said post and having its front end engaged with the said spring, an eccentric pivoted upon the rear end of the said finger and bearing upon the base plate, said eccentric being provided with longitudinally extending spaced V-shaped grooves in its periphery, and a tapered stop element on the base plate arranged to engage in one of said grooves to yieldably retain the eccentric in a set position.

5. In an apparatus for the purpose set forth, the combination of a brake shoe, tension devices cooperating with the said shoe, a plunger disposed normally tangential to the shoe and pivotally connected therewith, means for checking the pivotal movement of the plunger, an abutment arranged in the path of movement of the plunger adjacent

the front end of the same, and plunger guiding and retaining means associated with said abutment.

6. In an apparatus for the purpose set forth, the combination of a brake shoe, tension devices associated with the brake shoe, a pair of lugs on the brake shoe between the ends of the same, a plunger disposed between the said lugs and pivotally secured thereto, means for frictionally limiting the pivotal movement of the plunger, an abutment arranged in advance of the plunger and in the path of movement thereof, plunger guiding and retaining means associated with the abutment, and a yieldable element arranged adjacent the plunger guiding and retaining means and operating to check the forward movement of the plunger and imparting rearward movement thereto to return the same to its initial position.

7. In an apparatus for the purpose set forth, the combination of a brake shoe, tension devices cooperating with the brake shoe, spaced bosses on the shoe, a plunger disposed between and pivoted to the bosses, set screws mounted in the bosses and engaging the pivotal support of the plunger whereby to check the pivotal movement of the same, the plunger being longitudinally slotted through its rear portion, a clamping element engaged through the plunger to set the walls of the slotted portion toward each other, an abutment adjacent the front end of the plunger and in the path of the same, plunger guiding and retaining means associated with the abutment, and means for yieldably checking the forward movement of the plunger and imparting a return rearward movement thereto.

8. In an apparatus for the purpose set forth, the combination of a brake shoe, a tension device cooperating with the brake shoe, a plunger pivotally mounted upon the brake shoe and normally disposed tangential thereto, a box-like member rigidly supported about the forward end of the plunger, the said member having an open outer side to facilitate removal or insertion of the plunger and having a front wall constituting an abutment for the plunger, means mounted on said member for guiding and retaining the plunger, and means for yieldably checking the forward movement of the plunger and imparting a return rearward movement thereto.

9. In an apparatus for the purpose set forth, the combination of a brake shoe, a tension device cooperating with the brake shoe, a plunger pivotally mounted upon the brake shoe, a box-like member housing the front end of the plunger and having a front wall constituting an abutment for the plunger, nuts mounted on the front end of the plunger to impinge against the said abutment and adjustable longitudinally of the

plunger to define the range of its movement, guiding and retaining elements secured upon the box-like member and engaged with the plunger to guide and support the same in its movement, an expansion element disposed in rear of the said guiding and retaining elements, and means on the plunger for adjusting the tension of the said element and receiving the thrust of the same where 5
10 by the forward movement of the plunger will be yieldably checked and rearward return movement imparted thereto.

10. In an apparatus for the purpose set forth, the combination of a brake shoe, a tension device cooperating with the brake shoe, a plunger mounted upon the brake shoe, a box-like housing for the front end of the plunger, said housing having a part constituting an abutment for the plunger, 15 impact nuts mounted upon the front end of the plunger and adjustable toward and from the said abutment, a collar secured upon the 20

plunger at the rear of the said nuts, guiding and retaining plates secured on said housing above and below the plunger and engaged with the rear end of said collar, a washer mounted upon the plunger against the rear side of said plates, a sleeve bearing against said washer, a cushion housed in said sleeve, and nuts mounted on the plunger and providing a bearing for the rear end of said cushion. 25

11. In an apparatus for the purpose set forth, the combination of a brake shoe, tension devices cooperating with the brake shoe, a plunger pivotally mounted on the brake shoe, means for frictionally resisting pivotal movement of the plunger, an abutment in the path of the plunger, and means for yieldably checking movement of the plunger 30 toward the abutment and imparting a return movement thereto. 35

In testimony whereof I affix my signature.
TELESPHORE C. DEMERS. [L. s.] 40
